Inventor:

William Franklin Couter

UNITED STATES PATENT OFFICE.

WILLIAM FRANKLIN COUTER, OF PALO ALTO, CALIFORNIA.

SHOTGUN SHELL.

Application filed April 14, 1924. Serial No. 706,439.

To all whom it may concern:

Be it known that I, WILLIAM FRANKLIN COUTER, a citizen of the United States, residing at 650 Coleridge Ave., Palo Alto, county of Santa Clara, State of California, have invented a new and useful Improvement on a Shotgun Shell, of which the following is a specification.

This invention relates to an increase of range on the present shotgun shell by means of a metallic cylinder that will make a thirty (30) inch pattern at a distance of ninety (90) yards instead of at forty (40) yards distance, the capacity of the present shell. This metallic cylinder which is to be inserted in the shell will carry the shot firmly together a distance of fifty-five (55) yards maximum before spreading.

Figures 1 and 2 show a cross section of the shell when loaded and also when discharged.

Figures 3 and 4 show similar views in elevation.

Wads C and E are attached together by cord F, wad C is placed in the shell, wad E is placed in end of cylinder, wads C and E and cylinder are placed in shell and then charge of shot inserted with wad B as cap-

ping. When shell has been discharged, the cylinder, wads E and C travel firmly together a distance of fifty five (55) yards. The resistance on wad C separates wads C and E, causing cylinder to discharge shot in the same manner as when leaving muzzle of gun. Then the shot proceeds to spread in the regular way. Now the cylinder will discharge the shot at forty (40) yards by uniting C and D. These two wads C and D attached together give them more resistance therefore separating from cylinder forty (40) yards.

Exterior of cylinder is to be coated with felt, so as to give a smooth surface against interior of barrel. This will give less wear and spreading of choke of gun than the shell now on the market.

I claim:

A cartridge comprising a shell with its propelling charge, a wad, and a shot container flexibly connected with said wad, whereby the air resistance on said wad will cause the separation of said container from the shot in flight.

WILLIAM FRANKLIN COUTER.
